UNITED STATES PATENT OFFICE.

RALEIGH McCORMICK, OF ST. LOUIS, MISSOURI.

DESIGN FOR A TREAD-LINK FOR TIRES.

59,904.

Specification for Design.

Patented Dec. 6, 1921.

Application filed July 16, 1921. Serial No. 485,307. Term of patent 14 years.

To all whom it may concern:

Be it known that I, RALEIGH McCORMICK, a citizen of the United States of America, residing in the city of St. Louis, State of Missouri, have invented a new, original, and ornamental Design for a Tread Link for Tires, of which the following is a specification, reference being had to the accompanying drawing, forming part thereof.

Figure 1 is a perspective view of a tread link for tires, showing my new design.

Fig. 2 is a plan view thereof.

Fig. 3 is a vertical cross section through the link.

I claim:

The ornamental design for a tread link for tires, as shown.

RALEIGH McCORMICK.
